CLAIM

The ornamental design for a portable media player, as shown and described.

DESCRIPTION

FIG. 1 is a perspective view of a portable media player showing embodiment 1 of my new design;

FIG. 2 is a front elevation view of a portable media player showing embodiment 1;

FIG. 3 is a rear elevation view of a portable media player showing embodiment 1;

FIG. 4 is a right elevation view of a portable media player showing embodiment 1;

FIG. 5 is a left elevation view of a portable media player showing embodiment 1;

FIG. 6 is a top plan view of a portable media player showing embodiment 1;

FIG. 7 is a bottom plan view of a portable media player showing embodiment 1;

FIG. 8 is a rear side perspective view of a portable media player showing embodiment 1;

FIG. 9 is a perspective view of a portable media player showing embodiment 2 of my new design;

FIG. 10 is a front elevation view of a portable media player showing embodiment 2;

FIG. 11 is a rear elevation view of a portable media player showing embodiment 2;

FIG. 12 is a right elevation view of a portable media player showing embodiment 2;

FIG. 13 is a left side elevation view of a portable media player showing embodiment 2;

FIG. 14 is a top plan view of a portable media player showing embodiment 2;

FIG. 15 is a bottom plan view of a portable media player showing embodiment 2; and,

FIG. 16 is a rear side perspective view of a portable media player showing embodiment 2.

Any shading and cross-hatching are not features of the design but are utilized to illustrate the surface contours of the portable media players designs in the drawings.

(Continued)

The broken lines in the drawings depict portions of the portable media players that form no part of the claimed designs.
